UNITED STATES PATENT OFFICE.

LANSING ONDERDONK, OF BOSTON, MASSACHUSETTS, ASSIGNOR TO THE UNION SPECIAL SEWING MACHINE COMPANY, OF CHICAGO, ILLINOIS.

SEWING-MACHINE.

SPECIFICATION forming part of Letters Patent No. 577,878, dated March 2, 1897.

Application filed October 6, 1892. Renewed July 25, 1896. Serial No. 600,566. (No model.)

To all whom it may concern:

Be it known that I, LANSING ONDERDONK, a citizen of the United States, residing at Boston, in the county of Suffolk and State of Massachusetts, have invented certain new and useful Improvements in Sewing-Machines, of which the following is a description, reference being had to the accompanying drawings, and to the letters and figures of reference marked thereon.

My invention relates to sewing-machines, and particularly to that class known as "lock-stitch" machines, and comprises various improvements in the construction and operation of the parts of such machines.

The first object of my invention is to provide means for driving the loop-taker, timed with respect to the movements of the needle. Heretofore the advantage has been seen of giving to the needle two reciprocations to one revolution of the loop-taker, the latter having two hooks, so that during one revolution of the loop-taker two complete stitches may be formed, whereby the capacity of the machine over one in which the needle reciprocates once to each revolution of the loop-taker is doubled without any such increase of speed as would impair the durability of the machine. In this connection it has been heretofore proposed to provide machines with loop-takers having two hooks, but all such machines are more or less defective and differ in several important respects from my invention. In one of such machines it has been proposed to fix a revolving double-hooked loop-taker rigidly on the shaft, while in my construction the double-hooked loop-taker is held in position by a raceway, in which it revolves and in which position it is driven by an independent driver, which alternately engages and disengages the loop-taker at certain points in its rotation for the purpose of allowing the needle-thread to pass between it and the loop-taker. In the old machine

above specified there is no raceway, but the loop-taker, being fixed rigidly on the shaft, is supported and revolved by it, the difference between this construction and mine obviously being considerable both as regards the mechanical arrangement and the method of forming the stitch. It has also been pro-

posed to effect the said two-to-one motion by use of gears, the loop-taker being canted. Gears are noisy and likely to wear out quickly under high speed. In my construction they are dispensed with and the loop-taker is supported perpendicularly on its axis. Furthermore, in said old construction a very large bobbin or bobbin-case and reel is used. This is objectionable and in some cases impractical because of excessive chafing of the needle-thread.

Various other constructions and arrangements of mechanisms have been proposed for securing the relative movements of the needle and loop-taker, but all are more or less defective and impractical. I aim, therefore, to provide a practical arrangement for obtaining the desired movement in machines adapted to do a great amount of work and run at high speed.

Another object is to provide means coöperating with the two-to-one-motion mechanism referred to, whereby a variable speed is imparted to the loop-taker or other part to be driven, thus enabling said part to move at different rates of speed.

A still further object of my invention is to provide a thread-controlling mechanism operating in conjunction with the needle and loop-taker and timed for regulating the slackening and tightening of the thread at the proper moment to afford the best results in the production of the stitch. I eliminate from said thread-controlling mechanism the operating-cams, which have been in such general use in lock-stitch machines, against which there is great leverage and consequent wear. Thus I secure greater speed with less applied power, have less noise and wear in the running parts, and obtain an efficient and simple action in drawing in and setting the stitch.

Certain other objects have been aimed at in the construction of my machine, all having in view the simplifying and improving of the apparatus and the making of an organized machine capable of effective use.

My invention therefore consists in the matters hereinafter described, and referred to in the appended claims.

In the accompanying drawings, which illus-

trate the invention, Figure 1 is a side elevation of a sewing-machine embodying my invention. Fig. 2 is a bottom plan view. Fig. 3 is an end view of the machine, showing particularly the loop-taker. Fig. 4 is a similar view, some of the parts being omitted and certain other parts being in a different position. Fig. 5 is a plan view of a portion of the base-plate with the revolving loop-taker in place. Fig. 6 is a sectional view of the revolving loop-taker. Fig. 7 is a side elevation of the mechanism employed to impart a variable speed to the revolving loop-taker. Fig. 8 shows a double-shaft sewing-machine and the mechanism for imparting a two-to-one motion to the lower shaft. Fig. 9 is a detail end view of the connecting-rod and disk shown in Fig. 14. Fig. 10 is another form of the mechanism for imparting variable motion to the loop-taker. Fig. 11 is a detail of parts of Fig. 10. Fig. 12 shows another means for imparting variable motion to the loop-taker. Fig. 13 is a detail of parts of Fig. 18. Fig. 14 shows a side elevation of another form of mechanism for operating the needle-bar. Fig. 15 is an end view of Fig. 14. Fig. 16 shows a side elevation of a machine having double shafts and variable-speed mechanism, and Figs. 17, 18, and 19 are diagrammatic views of the two-to-one motion mechanism.

In the following description I have termed the device which manipulates the needle-thread beneath the bed-plate a "loop-taker," and under this title I intend to be included all devices which manipulate the needle-thread to form a chain-stitch, single or double, a lock chain-stitch, or a lock-stitch of any character. To make these various stitches, the loop-taker may or may not carry a lower thread, or the lower thread may be supported or guided independently of the loop-taker. My loop-taker as employed in the machine described carries a bobbin and bobbin-case, is provided with two loop-taking hooks, each having a beak and a heel, and is provided with other features that are hereinafter described and which render it efficient for the purposes set forth.

In the drawings, A represents the base-plate 50 of the machine.

B is the main shaft, driven from a suitable source of power by means of a belt trained over the wheel A'. The needle-bar-actuating lever or bar a is operated from the main shaft 55 B by the eccentric connecting-rod a' in the usual manner and is pivoted on the main frame or gooseneck A^2 of the machine.

G is the needle-bar, to which is attached the needle in the ordinary manner.

60 The main shaft is made in two parts B B', the part B being, as above mentioned, the main shaft of the machine, from which the needle-bar and feed are operated by connections, as shown. The shaft B' is so connected with and driven from the shaft B that the loop-taker D, driven from the shaft B', makes one revolution while the needle-bar is re-

ciprocated twice and the shaft B makes two revolutions, whereby, as the loop-taker is a double-hooked one, two stitches are made 70 during one revolution of the loop-taker, thus increasing the capacity of the machine. This movement is accomplished in the following manner: The shafts B and B' are arranged with their longitudinal axes eccentric to each 75 other, as clearly shown in Figs. 2 and 10. To one end of the shaft B' is secured a disk b' , having two grooves or slots $b^5 b^6$ across its face, as shown in Fig. 17, these grooves crossing each other at right angles, the point at 80 which they cross being exactly central with the shaft B'. A collar b is secured on the shaft B and is provided with two studs $b^2 b^3$, the centers of which are equidistant from the center of the driving-shaft B, this distance 85 between the center of the shaft B and the studs being equal to the distance between the centers of the shafts B B'. These studs may be made to turn in sockets formed in the collar b , or may be made rigid, but, at any rate, 90 that portion of the studs $b^2 b^3$ entering the grooves $b^5 b^6$ should be made to fit the same exactly.

In Fig. 18 is shown the relative position of the centers of the disk b' and collar b , which 95 are the same as the centers of the shafts B and B', to which they are rigidly secured. It also shows one of the driving-studs b^2 of the collar b at the center of the slots $b^5 b^6$. Were it not for the other driving-stud b^3 in the slot b^6 , or, in other words, if there were no other connection between $b^5 b^6$ than the driving-stud b^2 and the two shafts B and B' were to stop in position to bring the stud b^3 directly over the center of B', it is evident that the driving-shaft B in that position loses control of the driven shaft B', and this shaft and all the connections are in a position to be turned in any direction, either by any strain on the hook D by the needle-thread, by the inertia 105 of its movement, by hand, or by any other cause independent of the shaft B; but with the driving-stud b^3 operating in the slot b^6 , as does the stud b^2 in the slot b^5 , then it is evident that when either driving-stud is in the center of the disk b' , and, secondly, of the shaft B', the other driving-stud controls the movement of the disk b' .

It will of course be understood that were 110 there only one slot in the disk and one connection between the disk and collar, that connection, for example, moving in the groove b^5 of the disk, and that the distance of the center of the driving-shaft B (and therefore the collar b) to the center of the connection 115 engaging the slot b^5 is the same as the distance between the two shafts B and B', as shown in Fig. 18, in the revolving of the shaft B said connection, being the stud b^2 , must pass directly into the center of the shaft B'. 120

Assuming that we commence the revolution of the shaft B with the stud b^3 and slot b^5 at the point occupied by stud b^2 and slot b^6 , now as we move on until we come to the po-

sition of the stud b^3 we find that shaft B has made one-half a revolution and the disk b' one-fourth of a revolution. Going on to the point of beginning we find that the shaft B has made a full revolution and the disk b' has made one-half of a revolution. Thus it is evident that it requires two revolutions of the shaft B to effect one revolution of the disk b' . It is also evident that the line traveled crossing the disk is that of the slot, which is straight. Therefore, as a natural consequence, if the collar is provided with a second stud equidistant from center to center and opposite from the first and on a line with the center of the shaft the line described across the face of the disk b' would be the same as that traveled by the first stud, except at right angles with it, the centers of the two lines being common with that of the shaft upon which the disk revolves. I have found that instead of being round at the points where the studs fit the grooves a block is preferable, but however arranged all lines and centers should be substantially as above. By this construction all noise is obviated, and for a two-to-one motion the same is preferable to the use of gears, being less noisy, less liable to wear out, and better, especially when high speed is desired; and, furthermore, not being as sensitive to wear there is very little liability of any lost motion between the loop-taker and needle.

The two slots in the disk b' and the two studs on the collar b are not necessary to produce the particular movement of the shafts B and B' with respect to each other, and one slot and one stud may be dispensed with, the other two being necessary only to overcome the possibility of the driving-shaft losing control of the driven shaft when the stud of the collar b is passing over the dead-center of the disk. Hence I may use the construction shown in Fig. 19, in which is represented a disk b' with a single slot and a single stud on the driver b , the arrangement of the shafts being the same as in Fig. 18. In order to prevent a retrograde movement of the driver-shaft in this form of driving mechanism, I provide the disk b' with studs 1 and 1^a, placed on a line at a right angle to the slot b^5 and equidistant from the axis of the shaft B'. The driver b , at a point opposite the attachment of the driving-stud b^2 , is notched for the reception of said studs 1 1^a. Bearing in mind that the driving-shaft B makes two revolutions to one of the driven shaft B', it will be seen that as the driving-stud b^2 changes positions with the notch in the driver, thus making a half-revolution, the stud 1^a will make but one-quarter revolution and will pass out of said notch. This quarter-revolution will cause studs 1 and 1^a to assume a position one above the other or in a vertical plane viewing Fig. 19. Another half-revolution of the driving-shaft B in the same direction will cause the notch in the driver to reassume the position of Fig. 19 and cause the stud 1 on the disk b' of the driven shaft to enter said notch. Thus it

will be seen that the driver never loses control of the looper-shaft and prevents any retrograde movement thereof. In Fig. 18 this construction has its equivalent in the stud b^3 and slot b^6 .

While in the sewing-machine forming the subject-matter of the present invention I have found the mechanism for imparting the two-to-one motion very useful, it will be understood that in certain features I am not limited to the particular operating connections between the shafts B and B'.

In Fig. 7 I show a machine which in its general construction is similar to that shown in Fig. 1, but which is capable of giving a variable motion to the loop-taker D by reason of the disposition of the main driving mechanism. This variable motion of the loop-taker is desirable for the purpose of making the loop-taker move faster in some portions of its movement than in others, so as to move rapidly in entering the loop of needle-thread and at the same time enable the preceding loop carried by the other hook of the loop-taker to reach a position to be drawn up sooner than it would if the loop-taker is running at uniform speed. This also permits of the thread-delivery opening or space of the race to be made much smaller. The shaft B is supported in bearings or hangers a^2 and a^3 and the shaft B' in the bearing or hanger a^4 , but I add a third shaft J' to the machine, which is supported in the hanger a^5 , which shaft J' actuates the loop-taker shaft B'. In this figure xx , xx' , and xx^2 , with the shaft J', are the extra parts which make up the variable-motion mechanism. It is necessary for this purpose to have the driving-shaft and the driven shaft out of alignment, the same as is necessary to get a two-to-one motion. Therefore this figure shows a prime shaft B and loop-taker shaft B' on the same line, with all the necessary variation in the secondary shaft J'. xx^2 is a collar secured to the prime shaft B, in which there is secured a stud. xx is a disk to which is also secured a stud, and the connection between xx^2 and xx is by means of a link xx' , which works freely on the studs secured in xx and xx^2 . As the lines of the shafts B and J' are not the same, the driving-pin of the collar xx^2 naturally passes closer to the center of xx during a certain portion of the revolution of the shaft B than it does at others. When going to the center of xx , the speed must naturally be increased, and when going from the center gradually diminished. Therefore whatever motion is given to the disk xx must be given to the primary shaft J', to which it is secured, thence through the connections b b' and loop-taker shaft B' to the loop-taker D, the whole arrangement being so timed as to give the loop-taker D the advantage of the increased speed at the proper instant. It is old in single-hook machines to hurry forward the hook at a certain portion of its movement, but in the present machine the principal advantage is

in hurrying the loop-taker at the time for it to enter the needle-loop and to hurry it so as to enable the space between the front and rear ends of the hook-race to be made less.

5 Figs. 8 to 16, inclusive, show different forms of my invention in which a double-shaft sewing-machine is employed, and show various ways in which variable motion may be obtained, and also means for actuating the needle-bar.

In Figs. 8 and 9 I show portions of a double-shaft sewing-machine in which variable motion is imparted to the loop-taker driving-shaft B by means of a link A⁵, which connects the principal shaft A⁴ with the lower shaft B. The shaft A⁴ is provided with a crank a⁴, to which one end of the link A⁵ is connected by the bearing a⁵. The link A⁵ has an enlarged portion A⁶ near its central portion, and has a slot a⁶, in which a block a⁷ is fitted. A fulcrum-pin A⁷ passes through said block and is rigidly secured to the frame of the machine. The lower end of the link A⁵ has a stud a⁸, which engages a disk b¹² 25 upon the end of the shaft B. This disk has a single groove across its face, and a portion of its periphery parallel with the groove is flattened, as shown. The stud a⁸ is secured at a point opposite the center of the shaft B 30 when the crank a⁴ is at its lowest point. The fulcrum-pin A⁷, being nearest the lower shaft, causes the stud to travel in an elliptical path. The shaft A⁴ travels twice as fast as the lower loop-taker driving-shaft B. A lug a⁹ upon 35 the link A⁵, located just above and close to the flattened portion of the disk b¹², prevents any tendency of the lower shaft to run ahead or back at the time when the stud a⁸ has no control of the disk b¹² by reason of its being 40 central with the shaft B, and this lug serves the same purpose as the second stud b³ in the collar b. (Shown in Fig. 1.)

Fig. 10 shows a machine in which the needle-bar is to be driven by a revolving shaft 45 in a manner similar to that described in connection with Figs. 8 and 9, having a fixed fulcrum over which the driving-lever rocks and thus imparts its crank motion (upper shaft) to the lower shaft. The parts xx xx' xx³ are 50 substantially the same as the corresponding parts in Fig. 7, the only difference being that instead of the shaft B and the collar xx³ in said Fig. 7 a lever is used, a stud being secured thereon in a manner similar to that in 55 which it is secured in the collar xx³. The link xx' turns on the stud of the connecting or driving lever in the same way as the collar xx³ in Fig. 7. The driving-lever at the point 60 the stud and link are secured to it describes a circle a portion of which passes near to the center of xx, while the other portion passes from it, thus giving the shaft B, the shaft B', and consequently the loop-taker D a variable motion similar to that secured by the arrangement shown in Fig. 7.

65 Fig. 11 is an end view showing the mech-

anism for securing the variable motion described in connection with Fig. 10.

In Fig. 16 a sewing mechanism is represented having a needle-driving shaft and a loop-taker driving-shaft. The main feature is that instead of reducing the revolutions of the loop-taker to one-half that of the driving-shaft the speed of the needle-driving shaft is increased just twice. The driving-shaft to 75 which the belt-wheel is attached runs at the same rate as the shaft which drives the loop-taker D. Consequently to increase the operations of the needle-bar to twice that of the loop-taker the two-to-one-motion devices employed to reduce the revolutions of the loop-taker D are applied to the needle-bar driving-shaft in a reverse manner. For example, instead of the collar b being the driver and the disk b' the driven part in the present construction just the reverse takes place; also, in the machine here shown the lever driving the lower shaft and called the "driving-lever" has a sliding fulcrum-pin, thus causing the end of the driving-lever which carries the 80 stud to describe a true circle when placed centrally, which would not be the case were the fulcrum-pin stationary, as described in connection with Fig. 8. I provide in connection with this a disk having a slot, in which 85 slot the stud of the driving-lever engages, and the arrangement is such as to give the loop-taker shaft a variable revolving motion. The same arrangement as xx xx' xx³ (shown in Fig. 10) could be substituted. The connection 90 between the needle-bar staple and the needle-bar is a simple link connection. As shown in Figs. 14 and 15, however, this arrangement may be varied and a variable motion of the needle-bar provided by the cross-head or cam 95 connection, as shown.

Figs. 12 and 13 represent, respectively, side and end views of a construction of lower portion of variable-motion mechanism substantially the same as shown in Fig. 16.

In the figures referred to I have shown mechanism for giving a two-to-one motion for reciprocating the needle-bar twice to one revolution of the loop-taker, or vice versa. I have accomplished this either by having the speed 115 of the needle-bar normal and reducing that of the hook or by leaving the speed of the hook normal and doubling that of the needle-bar, and these movements have been accomplished by arranging the mechanical connections between the driving and driven shafts either above or below the bed-plate. Furthermore, I have shown in connection with this mechanism for giving the two-to-one motion mechanism for retarding and accelerating the 120 speed of the loop-taker at different portions of its movement.

At the front end of the shaft B' is secured the loop-taker driver E. This shaft is supported in a hanger depending from the base-plate A, and secured to the hanger are the plates C C', which form the loop-taker race.

The plate C is provided with an annular groove C², while plate C' is plain, but when the two plates are united a groove or channel is formed and in this the loop-taker D revolves when actuated by the driver E.

The feeding mechanism which I have described and illustrated in Figs. 1 and 2 and which I have found useful in this machine is not herein claimed, since it forms the subject-matter of an application filed by me July 20, 1892, Serial No. 440,635. This feeding mechanism consists of a lever 5, connected by a ball-and-socket joint 6 at one end to the feed-bar 7 and at the other end to the eccentric rod 2, which is driven from the main shaft of the machine and has a lateral stud 3 journaled on an oscillating support and attached to the frame of the machine. The rise and fall and backward and forward movements of the feed-bar 7 and feed-bar 10 are regulated by the working fulcrums 15 and 18, the former of which is secured to the bar 16, sliding on ways 11 and 12, said bar being held in any desired position by bolt 13 and set-nut 14. The rocking fulcrum 15 regulates the forward and backward movement of the feed, while the rise and fall is governed by the fulcrum 18 at right angles to the part 15.

I have herein illustrated a form of thread-controlling device which I propose to use in connection with the two-to-one motion and variable-speed motion hereinbefore described, this thread-controlling device being illustrated in Figs. 1 and 3 and its object being to control the drawing of the thread up close to the material when the needle-bar is rising to its highest point and to retard the thread sufficiently in the descent of the needle-bar to prevent the slack of the thread getting in the way of the needle-point, and, furthermore, to provide a device working in connection with a revolving loop-taker moving at even or varying rates of speed, so that a variation of time of drawing the slack thread from the loop-taker may be permitted.

a²⁰ and b²⁰ are thread-eyelets on the goose-neck of the machine, and 27 the tension device, which may be either vertical or horizontal, as desired. The needle-bar lever a is of ordinary construction and is operated in the usual manner from the main shaft of the machine. It gives reciprocatory movement to the needle-bar G, carrying the needle e²⁰. Upon the upper end of the needle-bar are eyelets f²⁰ and f²⁰⁰, through which the thread passes on its way to the needle. The thread may be passed from the tension device through the eyelet b²⁰ and thence through the adjustable eyelet g²⁰, attached to the frame of the machine, through eyelets f²⁰ f²⁰⁰ (or one of them) to the needle, but by this construction the objects aimed at by me are not accomplished as fully, and I have therefore devised the mechanism which I am about to describe.

Supported by the collar or band D²⁰, which supports the presser-foot bar and through

which the needle-bar reciprocates, is a shank h²⁰, preferably slotted on its lower end, so as to be vertically adjustable by means of a set-screw i²⁰. This shank h²⁰ has a hook k²⁰ formed on its upper end, this hook being arranged in a vertical plane between the vertical planes in which the eyelets f²⁰ f²⁰⁰ are placed and so located in respect to them that in the raising to its highest position of the needle-bar the eyelets f²⁰ f²⁰⁰ will be carried above the hook and in moving to its lowest position will be carried below the same.

In the operation of the machine when the needle-bar moves upward the thread between the eyelets f²⁰ f²⁰⁰ will be caught by the hook k²⁰ and form a loop in the thread, as shown in Fig. 1, thus acting to draw the needle-thread up tight against the material. In order to prevent too much slack in the thread around the needle when the needle-bar descends to its lowest position, I secure to the shank h²⁰, preferably at the lower end, a spring l²⁰, which, as shown, encircles the hook k²⁰ and bears upon the thread on both sides of said hook. This spring in the downward movement of the needle-bar retards the descent of the thread, and thus prevents the slack in the thread around the needle-point coming in the way thereof and curling around the same, rendering it liable to break. By making the hook and spring vertically adjustable an advantage accrues in that it enables the operator to hurry or delay the time of drawing the slack thread from the heel of the hook and at the same time take up and give a greater quantity of slack thread for the needle to form the loop of the succeeding stitch preparatory to the hook entering it.

Another advantage of this combination between the eyelets f²⁰ f²⁰⁰ and the hook and spring is that the stroke of the needle-bar may be less than otherwise required to draw up the slack of the needle-thread necessary to pass around the hook, since the needle-thread is practically drawn double between f²⁰ and f²⁰⁰. It will be understood that the hook and spring are adjustable at the height necessary to draw a tight stitch. By this construction also the drawing up of the thread to the material is accomplished quickly and when the needle-bar is near the upward extremity of its movement.

Various changes in the construction may be made without departing from the spirit of my invention, as, for example, different forms of take-ups or thread-controllers might be substituted for that herein shown. I have found this double-thread-eyelet arrangement which I have described and shown very advantageous in its results when applied to revolving-hook machines for the reason that in such machines the object is not to draw off from the heel of the hook until the latter has traveled almost to the needle. In other words, by using double eyelets with the adjustable controller it is not required to begin to draw the thread up to the material until

the heel of the revolving hook has almost reached the needle, and consequently the opening in the hook-race need not be so large as would otherwise be the case and the race 5 therefore wears better.

A rotating loop-taker D, herein shown as provided with two hooks d d' , though, if desired, any number of hooks may be provided, revolves in the race C C', constructed as follows: The plates C C' are secured to the hanger on the under side of the work-plate by the screw s, the plate C' being arranged outside the other and having an annular rib, so that when the plate C, which is arranged 10 behind the loop-taker D and against the supporting-hanger, is secured to the plate C' a groove is formed, in which the loop-taker rotates. It will thus be seen that by making the ring C thinner or thicker the loop-taker 15 will be brought farther from or nearer to the needle, the same forming a spacing-plate by means of which also the wear may be taken up. These plates may be made of antifrictional material, such as wood fiber, so that 20 oiling will be unnecessary and at the same time prevent cutting or grinding out. The use of oil is objectionable, owing to the liability of the bobbin and needle-thread becoming soiled by contact therewith. By the 25 use of the antifrictional material this is completely avoided and a very satisfactory result is attained.

H is a loop-spreader herein shown as attached to the race-plate C and triangular in 30 shape, its apex forming a beak which curves close to the path of the needle and in line close above and central with the hook of the loop-taker, so that when the hook shall have entered the needle-loop and is carrying it 35 forward it will carry it onto the beak of the spreader; or, in other words, as the loop moves forward with the needle-thread spread by the thickness of the hook owing to the beak of the spreader being pointed and its 40 relative position the hook will carry the needle-thread onto the loop-spreader, and the farther the hook moves forward the farther the thread will be carried onto the spreader and the wider will the loop of the needle- 45 thread be opened, which with the angle at which it is drawn and the tension on the thread will cause the thread to pass back around the loop-taker and bobbin sooner and easier than possible if left entirely to the 50 time and form of the loop-taker, and saves breaking of the thread by any strain that might occur if the loop-taker should fail to cast the thread off properly, which is a common occurrence in other machines. It also 55 deflects the needle-thread loop, ends of thread, &c., from the hook-race and prevents their being carried into it, thus preventing the thread becoming wedged or jammed in the race and possible derangement of the machine. This loop-spreader is of great importance, and I have herein shown it as attached to one race-plate and covering both 60

plates in such a manner as to prevent the needle-loop from being caught between the plates where they are united to form the race. 70

The race-plates C C' are cut away directly beneath the feed-dogs, being flattened upon the side next the dogs. The cutting off of this portion of the race-plate forms thereby a tapering end portion, on the upper flattened 75 side of which is secured the said loop-spreader H. This construction facilitates the carrying of the new thread to the loop-spreader and assists in releasing the completed loop upon the other side after the projecting lip F' of the bobbin has moved so as to release it. About one-fourth of the entire circumference is cut away.

The double-hooked loop-taker D is actuated by a driver which is secured to the end 80 of the shaft B' and is provided with arms e e', which enter slots d' in the loop-taker. The shaft B' is slotted and the driver E is inserted and is secured in position by a pin e². The arms e e' are thrown into and out 85 of engagement with slots d' in the loop-taker D by means of a disk D², made, preferably, of wood fiber or other antifrictional material, provided with a cam-face so arranged that the arms will be caused to alternately 90 engage with and disengage from the loop-taker, the parts being so timed that when it is necessary to release the loop the arm at the upper side is not in engagement, but the 95 loop-taker will be driven by the other arm. 100 Thus it will be seen that at all times one or the other or both of the arms are in engagement with the slots in the loop-taker, so that there is always a positive connection between the loop-taker and its driving mechanism, and by the use of the thread-controller and variable-speed motion with the double-hooked 105 loop-taker I am enabled to draw the thread properly or take up the slack without necessitating a total disengagement of the loop-taker from its driver for an interval in order that the slack may be pulled up. For a greater portion of the distance of the rotation both arms e e' will be in engagement. A thread-guard e³, curved to conform to the 110 shape of the loop-taker, prevents the loop from being caught by the arms of the hook-driver. The thread-guard e³ is secured by a collar e⁴ to the shaft B' by means of the pin e². The thread-guard is slotted, so as to permit 115 the arms e e' to move in and out between the portions e⁵, which form a guard on either side of the driving-arms e e'. This thread-guard is omitted in Fig. 5, but shown in Fig. 7. The hooks of the loop-taker, as shown at d d', alternately enter and release the loops as the 120 loop-taker is revolved by the driver E. The center of the body portion of the loop-taker is provided with a recess, in the center of which is secured a pin or stud d², and on this pin or 125 stud the bobbin-case F is supported. The bobbin-case is formed with a projection F', cut from the shell. Heretofore it has been the practice to secure a lip or projection to a 130

bobbin-case by brazing, soldering, riveting, and the like, but the forming of the lip from the same piece of metal has an advantage, inasmuch as it is far less likely to break off and fall into the raceway or otherwise damage the machine while in operation. A bobbin-case controller or stop I with a suitable notch is attached, as herein shown, to the hook-race or any other suitable part of the frame of the machine. When the bobbin-case is placed in position, the integral projection F' is made to engage the notch in the stop I, and the latter being stationary the bobbin-case is kept steady and prevented from revolving with the loop-taker. These features are of peculiar value in a machine of the character described in that the distance of the controller from and its position relative to the needle, and the consequent line of draft upon the needle-thread in passing between I and F', are such as to afford the least possible resistance to the drawing in of the needle-thread and to cause such drawing in to take place at a time when the draft of the needle-thread is slow and easy and when resistance the least affects the drawing up of the threads preparatory to setting the stitch in the material, and consequently in a corresponding degree avoids breaking or drawing off too much needle-thread, which would be liable at an angle which afforded greater resistance, as in other machines of this character. Furthermore, the point of contact between I and F' is as far as possible from the center of the bobbin-case, which latter is supported upon the stud d² of the loop-taker, said stud revolving in the bobbin-case. As the loop-taker rotates and the bobbin-case is held from movement, there is naturally a certain amount of friction between the bobbin-case and the supporting-stud d² of the loop-taker D, which friction holds the projection F' in contact with the stop I with a certain amount of friction which the needle-thread has to overcome in passing between the projection F' of the bobbin-case and its controller I, and the resistance being least at the greatest distance from the friction-point between bobbin-case and loop-taker, because the leverage is the least, it follows that these parts I and F' by their arrangement and structure are such as to afford the advantages stated. The bobbin-case is provided with slots f² f⁴, and around a tongue f⁵, formed by said slots, the thread is passed, thereby giving a tension to the lower or bobbin thread.

In order to prevent the point of the needle from injury or breaking, I provide the bobbin-case with a slot f, so that the point will enter the same and not strike the bobbin-casing. On either side of the recess of the loop-taker in which the bobbin-case is supported are depressions D' D', which are of considerable importance, as they permit the slack bobbin-thread at the time when the needle-thread is being drawn tightly into the goods. As the bobbin-thread passes out

through these depressions from the bobbin it will be seen that in the revolution of the loop-taker the bobbin-thread would be drawn off.

As shown in Fig. 3, the hook d is at the point of entering the needle-loop, the loop that was taken by the preceding hook being clearly shown in the drawing. The advantage of two hooks is that the first stitch is finished upon drawing thread on the following stitch—that is to say, it will be seen that the take-up mechanism, controlled by the needle-bar, as previously described, draws the first loop from the heel of the loop-taker hook nearly up to the material and as closely as is desired, according to the adjustment of the thread guides or eyes. The final or tightening pull to set the first loop, forming the stitch in the material, is exerted by the second loop-taker hook, which enters the next succeeding loop of needle-thread, the spreading of said latter loop around the body of the loop-taker having the effect of drawing the remaining portion of the first loop tight and thus setting the stitch. The thread draws up through one needle-hole over the goods to the next needle-hole. Thus the round-top or bird's-eye stitch is obtained. In this Fig. 3 it will be seen that the loop-spreader H is about to spread the needle-loop which has just been formed.

In Fig. 4 the parts have moved, the driver E having carried the loop-taker D to a point where one of the loops is about to be released from the heel of the hook and pass up between the ends of the projection F' on the bobbin-case and the plate I, which is secured to the race-plate C'. It will be observed that the utmost freedom of movement of the needle-loops is possible until the loop passes into the notch i in the plate I. When these are reached, a slight resistance is exerted at the point of contact as the needle-loop is drawn up to the goods carrying the bobbin-thread inside its loop. With the needle-bar in the position shown in this figure, with the thread-controlling mechanism shown in Fig. 1, the thread is not drawn off as quickly at the heel of the loop-taker. This being the case it allows the hook D to travel farther toward the needle before the thread is required, and consequently the open space in the race may be less. Between the beak of one hook and the heel of the opposite hook at two opposite sides of the loop-taker D the body portion is cut away, so that only a thin casing surrounds the bobbin on two sides. Through this thinned portion slots d⁵, having an enlarged portion d⁶, are cut, so that the end of the needle will not become dulled or broken by striking the loop-taker. At its other end it narrows so that its width is just sufficient to permit an ordinary-sized needle to pass freely.

The back edge of the slot d⁵ comes just outside the line of the hook-beaks d d', for the purpose of forcing the needle, when the point is engaged by the wall of the slot, just out-

side the line of the beak to prevent the hook from striking it, the walls of the slot preventing displacement, so that the beak will surely enter the loop. The bobbin-latch L is pivoted 5 to the hanger supporting the hook-race and is held in engagement with the bobbin by means of a locking-lever M, which engages a notch l in the latch. One end of the locking lever or catch is engaged by a spring held in 10 the socket formed in the hanger. The latch L may be rocked on its center l' to either side, so that the bobbin is readily removed. By rocking the bobbin-latch in a plane parallel with the plane of rotation of the loop- 15 taker, as in my construction, a much better and safer means of securing the bobbin is provided. It has been the common practice to hinge the latch so that it would project in a perpendicular line to that of the rotation 20 of the bobbin and loop-taker, and hence any weakness in the hinge-joint or spring holding the latch affords possibility of the latch becoming disengaged by reason of the constant jar incident to the operation of the 25 machine and causes the liability of breakage of some of the parts by the bobbin-case flying out or becoming displaced. Furthermore, in the old form above mentioned, when the machine was lifted or turned out of the table 30 and the latch had been accidentally left down, the latch or some part of the machine or table would possibly become broken or injured. By my construction, however, in addition to the spring action of the latch, the depth of 35 the notch l, which is engaged by the locking-lever M, makes it impossible for the latch to become disengaged except by the operator.

Various modifications and changes in the 40 construction of the parts may be made by any one skilled in the art without departing from the spirit of my invention.

Having thus described my invention, what I claim, and desire to secure by Letters Patent, is—

1. The combination of the needle, a rotating loop-taker provided with a plurality of hooks rigid therewith, mechanism for imparting to the needle a plurality of reciprocations to 50 one revolution of the loop-taker, and continuous-rotary-motion mechanism comprising means for imparting to the loop-taker a multiplex variable motion whereby the motion of the loop-taker as a whole is accelerated and retarded a plurality of times in each revolution; substantially as described.

2. In a sewing-machine, the combination with a needle, a rotary loop-taker having a plurality of hooks, mechanism for imparting 60 to the needle a plurality of reciprocations during one rotation of the loop-taker, said mechanism involving means for varying the motion of the needle during such reciprocations, and continuous-rotary-motion mechanism comprising means for imparting to the loop-taker a multiplex variable motion whereby the motion of the loop-taker is accelerated 65

and retarded a plurality of times in each rotation to coöperate with the variable motion of the needle; substantially as described. 70

3. In a sewing-machine, the combination with a needle, means for reciprocating the same, and a rotary loop-taker having a plurality of hooks rigid therewith, of mechanism for imparting to the loop-taker as a whole rotary motion involving a duplex variation; 75 substantially as described.

4. In a sewing-machine, the combination with a needle, means for reciprocating the same, and a rotary loop-taker having a plurality of hooks rigid therewith, of mechanism for imparting to the loop-taker as a whole continuous rotary motion involving a duplex variation during each rotation; substantially 80 as described. 85

5. In a sewing-machine, the combination with a reciprocating needle and a rotary loop-taker having a plurality of hooks rigid therewith, of means for actuating said needle and loop-taker, the loop-taker-actuating mechanism comprising two speeding devices coöperating to impart to the loop-taker a duplex variation during each rotation; substantially 90 as described.

6. In a sewing-machine, the combination with a reciprocating needle and a rotary loop-taker having a plurality of hooks rigid therewith, of mechanism for imparting to the needle two reciprocations during one rotation of the loop-taker, and mechanism for imparting to the loop-taker as a whole variable motion during such rotation; substantially 100 as described. 105

7. In a sewing-machine, the combination with a reciprocating needle and double-hooked rotary loop-taker, of mechanism for imparting to the needle two reciprocations during one rotation of the loop-taker, mechanism for imparting to the needle a variable motion during such reciprocations, and mechanism for imparting to the loop-taker a variable motion during such rotation; substantially 110 as described. 115

8. In a sewing-machine, the combination with a prime shaft, a needle, means for operating the latter from the prime shaft, a loop-taker having a plurality of hooks, a loop-taker shaft, a secondary shaft, connections between the prime and secondary shafts for varying the speed of the latter, and connections between the secondary and loop-taker shafts for reducing the number of rotations of the latter relative to the former; substantially 120 as described.

9. In a sewing-machine, the combination with a reciprocating needle and a rotary loop-taker having a plurality of hooks of mechanism for imparting to the needle two reciprocations during one rotation of the loop-taker, means for imparting to the needle a slow motion while in the vicinity of its lowest position, and means for accelerating the motion of the loop-taker during the slow motion of the needle; substantially as described. 125 130

10. In a sewing-machine, the combination with a reciprocating needle and a rotary loop-taker having a plurality of hooks of mechanism for imparting to the needle two reciprocations during one rotation of the loop-taker, means for imparting to the needle a slow motion while in the vicinity of its lowest position and a rapid motion in ascending, and means for accelerating the loop-taker during the slow motion of the needle and retarding the loop-taker during the rapid motion of the needle; substantially as described.

11. In a sewing-machine, the combination with a reciprocating needle and a double-hooked rotary loop-taker, of mechanism for imparting to the needle two reciprocations during one rotation of the loop-taker, mechanism for imparting to the loop-taker a variable motion during such rotation, and the take-up mechanism timed with relation to the motion of the loop-taker to properly draw in the stitch; substantially as described.

12. The combination in a sewing-machine with a reciprocating needle-bar and needle and a double-hooked rotary loop-taker, of mechanism for imparting to the needle two reciprocations during one rotation of the loop-taker, means for imparting to the needle a variable motion during such reciprocations, and a take-up mechanism controlled by the movement of the needle-bar whereby the variable movement of the latter imparts the proper take-up action; substantially as described.

13. The combination in a sewing-machine with a reciprocating needle-bar and needle and a double-hooked rotary loop-taker, of mechanism for imparting to the needle two reciprocations during one rotation of the loop-taker, means for imparting to the needle a variable motion during such reciprocations, means for imparting to the loop-taker a variable motion during such rotation, and a take-up mechanism partially carried by the needle-bar and controlled thereby, whereby the variable movement of the latter imparts the proper take-up action; substantially as described.

14. In a sewing-machine, the combination with a reciprocating needle and a rotary loop-taker, having a plurality of hooks, of mechanism for imparting to the needle two reciprocations during one rotation of the loop-taker, means for imparting to the needle a slow motion while in the vicinity of its lowest position and a rapid movement in ascending, means for accelerating the motion of the loop-taker during the slow motion of the needle and retarding the loop-taker during the rapid motion of the needle, and a take-up mechanism operating to draw in the stitch during the slow motion of the loop-taker; substantially as described.

15. In a sewing-machine the combination with a prime shaft, a secondary shaft and a

loop-taker shaft, of connections between the prime and secondary shafts for operating the latter, connections between the secondary and the loop-taker shafts for reducing the number of rotations of the latter relative to the former, a loop-taker and complementary stitch-forming mechanism; substantially as described.

16. In a sewing-machine the combination with a driving-shaft and a driven shaft of connections between the two shafts for reducing the number of rotations of one relative to the other comprising a slotted disk on one shaft and a crank on the other shaft carrying a pin operating in the slot of the disk, and stitch-forming mechanism comprising a needle actuated from the driving-shaft to have a reciprocation for every revolution of the latter, substantially as described.

17. In a sewing-machine the combination with a driving-shaft and a driven shaft of connections between the two shafts for reducing the number of rotations of one relative to the other comprising a slotted disk on one shaft and a crank on the other shaft carrying a pin operating in the slot of the disk and suitable stitch-forming mechanism, said shafts being set out of line; substantially as described.

18. In a sewing-machine the combination with a prime shaft, a secondary shaft and a loop-taker shaft, of connections between the prime and secondary shafts, connections between the secondary and loop-taker shafts for reducing the number of rotations of the latter relative to the former, comprising a slotted disk on one shaft and a crank on the other shaft carrying a pin operating in the slot of the disk, a loop-taker, and complementary stitch-forming mechanism; substantially as described.

19. In a sewing-machine the combination with a driving-shaft and a loop-taker shaft, of connections between the two shafts for reducing the number of rotations of the latter relative to the former, comprising a disk carried by one shaft having diametrical slots arranged at a right angle to each other, and a crank on the other shaft having pins operating in the slots of the disk, a loop-taker, and complementary stitch-forming mechanism comprising a needle actuated from the driving-shaft to have a reciprocation for every revolution of the latter.

20. In a sewing-machine the combination with a prime shaft, a secondary shaft, and a loop-taker shaft, of connections between the prime and secondary shafts for operating the latter, connections between the secondary and loop-taker shafts for reducing the number of rotations of the latter relative to the former, comprising a disk carried by one shaft having diametrical slots arranged at a right angle to each other, and a crank on the other shaft having pins operating in the slots of

the disk, a loop-taker, and complemental stitch-forming mechanism; substantially as described.

21. In a sewing-machine the combination with a prime shaft, a secondary shaft, and a loop-taker shaft, of connections between the prime and secondary shafts for varying the speed of the latter relative to the former, connections between the secondary and loop-taker shafts for reducing the number of rotations of the latter relative to the former, a loop-taker, and complemental stitch-forming mechanism; substantially as described.

22. In a sewing-machine, the combination with a prime shaft, a needle, means for operating the latter from the prime shaft, a loop-taker having a plurality of hooks, a loop-taker shaft, a secondary shaft, connections between the prime shaft and secondary shaft for varying the speed of the latter and means between the secondary shaft and the loop-taker shaft for reducing the number of rotations of the latter relative to the former, comprising a slotted disk on one shaft and a crank on the other shaft carrying a pin operating in the slot of the disk; substantially as described.

23. In a sewing-machine, the combination with a prime shaft, a needle, means for operating the latter, a loop-taker having a plurality of hooks, a loop-taker shaft, a secondary shaft, connections between the prime shaft and secondary shaft for varying the speed of the latter, and means between the secondary shaft and the loop-taker shaft for reducing the speed of the latter relative to the former, comprising a disk carried by one shaft, and having diametrical slots arranged at a right angle to each other, and a crank on the other shaft having pins operating in the slots of the disk; substantially as described.

24. In a sewing-machine, the combination with a prime shaft, a needle, means for operating the latter, a loop-taker having a plurality of hooks, a loop-taker shaft, a secondary shaft, connections between the prime shaft and the secondary shaft for varying the speed of the latter, and means between the secondary shaft and the loop-taker shaft for reducing the speed of the latter relative to the former, consisting of an arrangement of the shafts whereby the axes will be eccentric relatively, a disk carried by one of said shafts and having diametrical slots arranged at a right angle to each other, and a crank on the other shaft operating in the slots in the disk; substantially as described.

25. In a sewing-machine, the combination with a prime shaft, a needle, means for operating the latter, a loop-taker having a plurality of hooks, a loop-taker shaft, a secondary shaft, means between the prime shaft and secondary shaft for varying the speed of the latter, comprising a crank on each shaft having a pin and a link connecting said pins, and connections between the secondary shaft and

loop-taker shaft for reducing the number of rotations of the latter relative to the former; substantially as described.

26. In a sewing-machine, the combination with a prime shaft, a needle, means for operating the latter, a loop-taker having a plurality of hooks, a loop-taker shaft, a secondary shaft, means between the prime shaft and secondary shaft for varying the speed of the latter, comprising an arrangement of the shafts whereby their axes will be eccentric relatively, and connections between the secondary and loop-taker shafts for reducing the number of rotations of the latter relative to the former; substantially as described.

27. In a sewing-machine, the combination with a prime shaft, a needle, means for operating the latter, a loop-taker having a plurality of hooks, a loop-taker shaft, a secondary shaft, means between the prime shaft and secondary shaft for varying the speed of the latter, consisting of an arrangement of the shafts whereby their axes will be eccentric relatively, a crank on each shaft having a pin, and a link connecting said pins, and connections between the secondary and loop-taker shafts for reducing the number of rotations of the latter relative to the former; substantially as described.

28. In a sewing-machine, the combination with a driving-shaft having a transverse slot at its forward end, a loop-taker driver pivoted within said slot having actuating-arms, a cam surrounding the shaft and actuating said driver, of a loop-taker race supported adjacent the driver and carrying a loop-taker having a series of openings for the reception of the arms of the driver, and also having a convex back, and a thread-guard supported by the driving-shaft adjacent the loop-taker extending lengthwise of the driver and slotted for its reception and passage, said guard being curved to conform to the convexity of the back of the loop-taker; substantially as described.

29. In a sewing-machine, the combination with the frame thereof, comprising a hanger, of a loop-taker race supported by said hanger, a bobbin-retainer pivoted to said hanger and confined to swing in a plane parallel with the wall of the race and provided with a notch in its lower extremity, and a spring-latch carried by said hanger and co-operating with said notch to hold the retainer in a vertical position; substantially as described.

30. The combination in a sewing-machine, with a reciprocating needle-bar and needle, and a rotary loop-taker having a plurality of hooks, of mechanism for actuating the loop-taker, mechanism for imparting to the needle-bar a plurality of reciprocations having a definite ratio with relation to a revolution of the hooks of the loop-taker, means for imparting to the needle-bar a variable motion during such reciprocations, and a take-up mechan-

ism controlled by the movements of the needle-bar, whereby the latter imparts the take-up action; substantially as described.

31. The combination in a sewing-machine with a reciprocating needle-bar and needle, and a rotary loop-taker having a plurality of hooks, of mechanism for imparting the requisite movements to the needle and loop-taker, a take-up mechanism controlled by the needle-bar for beginning the take-up action, and

means controlled by the loop-taker for finishing the take-up action; substantially as described.

In testimony whereof I affix my signature in presence of two witnesses.
